THERMOSTAT SOCKET

James L. Swift, Staten Island, and Thomas I. Halpin, South Farmingdale, N.Y., assignors to American District Telegraph Company, Jersey City, N.J., a corporation of New Jersey

Filed Aug. 15, 1969, Ser. No. 18,703

Term of patent 14 years

Int. Cl. D10—09, 99; D13—99
U.S. Cl. D52—7

FIG. 2.

FIG. 1.

FIG. 3.

FIG. 4.

FIG. 5.

FIG. 6.

FIG. 7.

FIG. 1 is a front elevational view of a thermostat socket embodying our design;

FIG. 2 is a right side elevational view of the thermostat socket of FIG. 1;

FIG. 3 is a left side elevational view of the thermostat socket of FIG. 1;

FIG. 4 is a top plan view of the thermostat socket of FIG. 1;

FIG. 5 is a bottom plan view of the thermostat socket of FIG. 1;

FIG. 6 is a rear elevational view of the thermostat socket of FIG. 1 with the cover plate removed; and

FIG. 7 is a rear elevational view similar to FIG. 6 but with the cover plate in place.

We claim:

The ornamental design for a thermostat socket, as shown and described.
